UNITED STATES PATENT OFFICE.

JAMES F. McLAUGHLIN, OF PHILADELPHIA, PENNSYLVANIA.

TYPE-WRITING MACHINE.

SPECIFICATION forming part of Letters Patent No. 406,292, dated July 2, 1889.

Application filed September 10, 1888. Serial No. 285,086. (No model.)

To all whom it may concern:

Be it known that I, JAMES F. McLAUGHLIN, a citizen of the United States, residing at Philadelphia, in the county of Philadelphia and State of Pennsylvania, have invented certain new and useful Improvements in Type-Writing Machines, of which the following is a specification.

My invention relates to improvements in type-writing machines in which a traveling carriage supporting the impression-cylinder is fed forward the space of one letter after each imprint of a type upon the paper; and its special object is to provide novel means for causing the carriage to be automatically returned to its starting-point when the end of a line of printing or writing has been reached.

In an application filed by me June 5, 1888, Serial No. 276,151, I have shown and described an automatic reverse movement for the carriage of an electric type-writer, and the invention herein shown and described is an improvement upon the same, the specific points of novelty of which will clearly appear from the following detailed description with reference to the accompanying drawings, which form a part thereof, and in which—

Figure 1 is a view in elevation of the rear of the carriage and letter-spacing mechanism supported in position upon the frame of the machine; Fig. 2, a similar view of the front of the carriage and the letter-spacing mechanism in their relative positions. Fig. 3 is an end elevation of the carriage and of a portion of the letter and line spacing mechanisms; Fig. 4, a plan view of the rear part of the carriage, showing the movable rack-bar and the sliding bar operating the same. Fig. 5 is a sectional elevation on line $\alpha\alpha$ of Fig. 4. Fig. 6 is a vertical sectional view of the ratchet, gear-wheel, and spring-barrel, constituting a part of the letter-spacing and reverse-motion mechanism. Fig. 7 is an interior view of the spring-barrel. Fig. 8 is a perspective view of the casting and pointer for gaging the end of a line of printing. Fig. 9 is a perspective view showing the relation of the sliding bar and locking-lever. Fig. 10 is a perspective view of the rear part of the carriage, showing the movable rack-bar, the sliding bar operating the same, and the sleeves and pins for guiding the rack-bar. Fig. 11 is a

perspective view of one of the guiding sleeves and pins detached. Fig. 12 is a sectional elevation of one side bar of the carriage, showing the guiding sleeve and pin, with the rack-bar secured to the latter; and Fig. 13 shows a section on line $z z$ of Fig. 12.

Like numerals of reference indicate like parts in all the figures of the drawings.

Referring now more particularly to Fig. 1, the base-plate or platform 1 of the machine is there shown supported upon legs 2 2, and two standards 3 3, mounted upon the rear end of the platform, have hinged to their upper ends 55 at 4 4 the guide-bar 4', upon which the rear portion of the carriage 6 is mounted by means of anti-friction rollers 5 5, so that when not otherwise obstructed the carriage may move along and upon guide-bar 4' from one end to 60 the other of the same. One anti-friction roller 7, secured to the front of the carriage and at about the center thereof, as indicated in Figs. 2 and 3, moves upon the front bar 8 of the frame of the machine, and when the carriage 65 is raised for inspection of the printing, as is usual in machines of this character, it will turn with the guide-bar 4' about the hinges 4 4. To the platform 1 is secured the framework 9, one part of which 9' extends below 70 the platform and is shaped like a rectangular box, and the other part, extending above the platform, is recessed at 10 and has there mounted upon a stud 11 a ratchet-wheel 12, gear-wheel 13, and a spring-barrel 14, the 75 functions of which will hereinafter more fully appear.

In the box-shaped portion 9' of frame 9 is secured an electro-magnet 15, and to a bracket 16 is pivoted the pawl-lever 17, carrying an 80 armature 18 in operative relation to the electro-magnet and a gravity-pawl 19, which is in engagement with the ratchet 12. To the upper free end of the pawl-lever is secured a stop-tooth 20, which is in position to engage 85 one of the teeth of gear-wheel 13 when the pawl-lever is actuated by the electro-magnet, and since the number of teeth in the gear-wheel 13 is equal to the number of teeth in the ratchet-wheel it will be seen that when 90 the pawl-lever is actuated by the electro-magnet and the ratchet is turned by the gravity-pawl 19 the stop-tooth 20 will limit the rotation of the ratchet to one tooth, since the 95 100

ratchet and gear-wheels are secured together, so that one cannot move without the other, as is indicated in Figs. 1 and 6. From the lower rear portion of the pawl-lever extends 5 a small rod 21, upon which a weight 22 is adjustable, and which serves to withdraw the armature or pawl-lever to its normal position when the electro-magnet is de-energized. A screw 23 passing through and adjustable in a 10 bracket 24, extending from frame 9, serves as a back stop of the armature or pawl-lever.

In the normal operation of my machine the pawl-lever 17 is actuated after each imprint upon the paper, and this is done either electro-magnetically, as indicated, or mechanically, in a manner clearly set forth in my pending application, Serial No. 276,151; but for the purposes of my present invention it is of no consequence by what agency the pawl-lever 15 is actuated, so long as it is understood that it will be actuated after each printing operation.

In Figs. 6 and 7 the ratchet, gear-wheel, and spring-barrel are shown in detail. The ratchet 25 and gear-wheels are secured together by screws, as indicated, and are loose upon stud 11. The gear-wheel itself is recessed upon one face, and the rabbed end of the spring-barrel enters said recess, while the other end 30 of the spring-barrel is accommodated within the recess 10, formed in the upper end of frame 9. The spring-barrel is also loose upon stud 11; but one end of its spiral spring 25 is secured to the stud, while the other end of the 35 spring is secured to the body of the drum or barrel. Thus it will be seen that while the ratchet and gear-wheels will necessarily move together they will be independent of the movement of the spring-barrel. The edge of the 40 latter is also provided with gear-teeth equal in number to the teeth of gear-wheel 13 and flush with the latter. Upon the carriage is mounted a rack-bar 26, extending throughout the whole length of the carriage and of such 45 width or thickness that the teeth of the rack-bar will normally engage the teeth of both the gear-wheel 13 and of the spring-barrel 14. It will now be understood that when by the operation of the pawl-lever the ratchet and 50 gear-wheels are rotated step by step the carriage upon which the rack-bar is mounted will be moved longitudinally, and by reason of the engagement of the rack-bar with the teeth upon the spring-barrel the latter will 55 also be rotated, and the spring 25 will be wound up step by step as the carriage advances toward the end of a line of printing. Thus as the carriage is fed forward power is stored in the spring, which, when permitted, 60 is sufficient to return the carriage to its starting-point. A gravity check-pawl 27, pivoted upon a bracket 28, which extends laterally from the upper end of frame 9, is used to prevent a partial return movement of the carriage 65 during the outward stroke of the pawl-lever.

Near the rear ends of the side bars 29 29 of

the carriage, and to the under side thereof, are secured sleeves 30 30, each of which receives a sliding rod 31, to the free ends of which the rack-bar 26 is secured, so that when said sliding rods are moved within the sleeves the rack-bar is shifted laterally, whereby it may be moved from the position where it engages the teeth of both the gear-wheel and 70 the spring-barrel to a position where it engages the teeth on the spring-barrel alone, as is indicated in Figs. 3 and 6. This lateral movement of the rack-bar is produced by a longitudinal movement of a rectangular sliding bar 32. This bar is guided in rectangular recesses 33, formed near the end of the sleeves 30, in the upper face thereof, and which are so deep as to cut through the shell of the sleeve. The sliding rods 31 are formed 85 flat at their upper face, and this flat portion is flush with the bottom of recess 33, as is best illustrated in Fig. 11.

From the flattened upper face of each rod 31 projects a short pin 34 into an inclined slot 35 in the rectangular sliding bar 32. There are two such slots in bar 32, one near each end of the bar, and each receives the pin 34 from one of the rods 31, and it will now be understood that when the bar 32 is moved 90 longitudinally within the recesses 33 the sides of slots 35 will act as cams upon pins 34 and will move the rods 31 within sleeves 30 30, thereby shifting the rack-bar 26, which is secured to these rods laterally. In one of its 95 positions the rack-bar will engage at the same time the teeth of gear-wheel 13 and of spring-barrel 14, and this position may be called the "normal" position of the rack-bar, while in the other or shifted position the rack-bar will 100 only engage the teeth of the spring-barrel 14, as indicated in Figs. 3 and 6.

The longitudinal sliding movement of bar 32 is accomplished by the following instrumentalities: A screw-rod 36, having a screw-thread of a rather high pitch, is journaled in bearings 37 38, fixed upon sliding bar 32. One of these bearings 37 is near the middle of bar 32, and the other 38 is at the right-hand end of the same, as will be seen by reference to 110 Figs. 1, 2, 4, and 5. A casting 39 (shown in perspective in Fig. 8) is shaped with a central boss, as shown, and with a downwardly-extending tail-piece 40. An arm 41, extending upwardly from the central boss, is provided 115 with a pointer 42 and with a pin 43, which is destined to actuate the alarm-bell ordinarily used in machines of this character for indicating the approach of the end of a line of printing. A rectangular slot 44, formed in the 120 central boss of the casting, receives the sliding bar 32, and a screw-threaded hole 45 receives the screw-rod 36, so that when the latter is turned by means of the milled head 36' the casting 39 will be moved along and upon 125 the sliding bar to the desired position, in which it may be fixed by the set-screw 46. (Indicated in Fig. 4.) As will be seen by reference to Figs. 2, 5, and 8, the upper extension 130

of casting 39, to which pin 43 is secured, forms one prong of a fork, of which the pointer 42 is the other prong, and by reference to Figs. 2 and 5 it will be seen that these prongs embrace a scale-bar 47, so that the pointer will indicate the position to which the casting has been adjusted.

When by the ordinary operation of the machine the carriage is moved forward step by step in the manner hereinbefore described, the tail-piece 40 of casting 39 will approach the middle of the supporting-frame 133 until it comes in contact with a stop 28', which is shown in Fig. 2 as a bracket secured to bracket 28 and extending upwardly into the path of the tail-piece. The sliding bar 32, to which casting 39 is fixed, is thus prevented from following the continued movement of the carriage, and as the latter is propelled onward bar 32 will be shifted longitudinally with relation to the carriage, or, rather, the carriage will be shifted with relation to bar 32, and by reason of the inclined slots 35 near the ends of said bar engaging the pins 34, projecting from rods 31 31, the rack-bar secured to the latter will be shifted laterally, as hereinbefore described.

As has been stated before, the normal position of the rack-bar is such that it engages at the same time both the teeth of the gear-wheel 13 and of the spring-barrel 14, and when shifted by the longitudinal displacement of bar 32 with relation to the carriage it engages the teeth of the spring-barrel alone. By the reaction of spring 25, which by this time has been put under tension, the barrel is rotated in the opposite direction, and the rack-bar and connected carriage are thus returned to their original position, as will now be readily understood by those skilled in the art. The rack-bar must be locked in either of its two positions, so that the carriage may be fed forward and then returned to its starting-point with security, and this is effected by a spring 48, secured to one of the side bars of the carriage, and engaging with a wedge-shaped tooth 49, formed at its free end, one of two V-shaped notches 50 50 in bar 32. The two notches are so spaced that one corresponds to the position of bar 32 when the rack-bar is in its normal position and the other to that position of bar 32 which it occupies when the rack-bar is in its shifted position. A slight or accidental mechanical impulse which the bar 32 may receive will not be sufficient to overcome the pressure of spring 48; but when said bar is forcibly acted upon spring 48 will yield and its tooth 49 will disengage one of the notches 50 and will allow the bar to be shifted with relation to the carriage until the other notch is engaged. The sufficiently powerful impulse for shifting bar 32 in one direction is furnished by the letter-spacing mechanism, hereinbefore described, and the sufficiently powerful impulse for shifting the bar in the other direction is furnished by the line-spacing mechanism. This

mechanism is substantially like the line-spacing mechanism illustrated and described with great minuteness of detail in my pending application, Serial No. 276,151, and since it forms no part of my present invention it need only be described sufficiently to explain its co-operation with the automatic reverse movement of the carriage.

To one end of the impression-cylinder 51 (shown in dotted lines in Figs. 2 and 3) is secured a gear-wheel 52, and a lever 53, pivoted upon the shaft of the cylinder, is provided with a gravity-pawl 54, the lower end of which only is visible in Fig. 3, the upper end, which engages the teeth of the gear-wheel 52, being hidden from view. The free weighted end of lever 53 is provided with an anti-friction roller 55, which bears upon the upper edge of a sliding bar 56, placed behind the front bar 29' of the carriage. The greater part of this sliding bar 56 is indicated in dotted lines in Fig. 2, and, as will be seen by reference to the drawings, one end of it is expanded to form an inclined plane 56', which is in effect a continuation of the upper straight edge of the main body of the bar. The other end of bar 56 is shaped cylindrically, as indicated at 57, and this cylindrical portion is guided in a sleeve 58, and is acted upon by a helical spring 58', which, when expanded, maintains the bar 56 in the position indicated in the drawings—i. e., with the inclined plane 56' just beyond the anti-friction roller 55. The bar 56 is also guided and is limited in its movements by a pin 59, projecting from its side and entering a slot 60 in the front bar 29' of the carriage. From about the middle of bar 56 projects a bracket 61 over the front bar 29' and down within a short distance from the upper edge of the front bar 8 of the supporting-frame of the machine. In this front bar 8 a series of holes 62 62 are provided, and a pin 63 may be inserted in and withdrawn from either of these holes. If the pin 63 is inserted, as shown, and if the carriage is reversed in the manner hereinbefore described, the bracket 61 will strike the pin, whereby the bar 56 will be stopped, while the carriage continues its reverse movement. The carriage is thus shifted with relation to bar 56, thereby compressing the helical spring 58' and causing the roller 55 to ride up the inclined plane 56', whereby the pawl-lever 53 is raised to the position indicated in dotted lines in Fig. 3. A partial rotation is thus given to the impression-cylinder, and the paper is fed forward for a new line between the impression-cylinder and a feed-roller 64.

The upward movement of the line-feeding pawl-lever 53 is utilized for returning the sliding bar 32 and thereby the rack-bar to their original normal position, whereby the reverse movement of the carriage is stopped. This is effected in the following manner: At that end of sliding bar 32 at which the bearing 38 for screw-rod 36 is formed there is also

formed a chamfer 65, and from the side of lever 53 a pin 66 projects laterally. Between chamfer 65 and pin 66 extends a two-armed lever 67, pivoted at about its middle to the side bar 29 of the carriage. The heavier arm of lever 67 is bent inwardly at its end, as shown at 68, and the lower end edge of this inwardly-projecting portion is beveled, as shown. Normally the heavy arm of lever 67 rests by its own weight upon the bottom of a U-shaped bracket 69, secured to the side bar 29, and in this condition of the machine the beveled end 68 of lever 67 is just out of contact with the lower edge of chamfer 65, or barely touches the same, while the other arm of lever 67, which extends over pin 66, is raised and is out of contact with the latter. The position of lever 67 in this condition of the machine is indicated in dotted lines in Fig. 3.

If now the carriage is fed forward by the letter-spacing mechanism during the ordinary operation of the machine, and arriving near the end of a line of writing, which is gaged by the position of casting 39, the sliding bar 32 at the rear of the carriage is moved toward the right to shift the rack-bar to be in engagement with the teeth of the spring-barrel alone, which at once reverses the carriage, as hereinbefore fully described. The movement of sliding bar 32 with relation to the carriage causes the beveled end of lever 67 to ride up the incline of the chamfer 65 and the other end of the lever is depressed to the position indicated in full lines in Fig. 3, bearing upon pin 66. When the carriage arrives near the end of its reverse movement, which is gaged by the position of pin 63 in one of the holes 62, the sliding bar 56 at the forward end of the carriage is shifted to the left with relation to the carriage, and the anti-friction roller 55 at the end of pawl-lever 53, riding up the inclined plane 56', raises said lever to the position indicated in dotted lines, whereby the line-feed is effected. At the same time the pin 66 raises the forward end of lever 67, which is now in its path, and thereby depresses the rear end of said lever, and the beveled end of which, acting upon the chamfer 65 like a cam, forces the sliding bar 32 back to its normal position, whereby the rack-bar is also shifted to its normal position in engagement with the teeth of both the spring-barrel and the gear-wheel 13. Thus it will be seen that sliding bar 32 and the rack-bar are shifted positively to bring the latter in its two positions for the regular letter-spacing and for the reverse movement. If now a new line of writing is produced and the carriage is again fed forward, the anti-friction roller 55 slowly descends the inclined plane 56' and the bar 56 is returned to its original position by the reaction of helical spring 58'.

In the drawings, Figs. 1 and 2, mechanism is shown for preventing the spring-barrel to unwind when the carriage is raised for inspection of the work. This mechanism forms

no part of my present invention and need not be described at length. When the carriage is raised—i. e., when it is up about the hinges 44—the rack-bar disengages the teeth of the spring-barrel, so that the latter would at once run down, and there would then be no power to effect the next reverse movement. To prevent this I have provided a pivoted pawl 70, weighted at its rear end, so as to bring its tooth normally out of engagement with the spring-barrel. This weighted rear end of pawl 70 rests upon the depressed portion of an eccentric 71, keyed to a rotary shaft 72, which is turned by a pitman 73 and crank 74, connecting the shaft with the guide-bar 4', upon which the carriage moves and which turns with the latter about the hinges 44. Thus when the carriage is raised and before the rack-bar disengages the teeth of the eccentric is moved under the rear part of pawl 70 and the tooth of the latter engages one of the teeth of the spring-barrel, and thus prevents the unwinding of the spring.

It is evident from the foregoing description that numerous changes in the details of construction may be made without in any way departing from the essence of my invention, and that I am therefore not limited to the exact details herein shown and described.

I claim as new and desire to secure by Letters Patent—

1. In a type-writer having automatic letter and line spacing mechanisms, the combination, with such mechanisms and a spring-barrel for storing power during and by the letter-spacing operation, and for reversing the carriage automatically when the end of a line of writing is reached, of a shifting rack-bar upon the carriage, which in one position actuates the spring-barrel and in the other position is actuated by the same, mechanism for shifting the rack-bar automatically in one direction by the letter-spacing movement of the carriage, and mechanical connection with the line-spacing mechanism for shifting the rack-bar automatically in the other direction, substantially as described.

2. In a type-writer having automatic letter and line spacing mechanisms, the combination of a spring-barrel for storing power during the letter-spacing operation and a shifting rack-bar upon the carriage actuating the spring-barrel in one position and actuated by the same in another position, with a sliding bar for shifting the rack-bar, positively actuated in one direction by the letter-spacing movement of the carriage and in the other direction by the line-spacing mechanism, substantially as described.

3. In a type-writer having automatic letter and line spacing mechanisms, the combination of a spring-barrel for storing power during the letter-spacing operation and a rack-bar upon the carriage in gear with the spring-barrel, with a gear-wheel normally engaging

the rack-bar for advancing the carriage step by step, a sliding bar for shifting the rack-bar out of and into engagement with the gear-wheel, a fixed stop in the path of the sliding bar for actuating the latter positively in one direction, and a lever operated by the line-spacing mechanism for actuating the sliding bar positively in the other direction, substantially as described.

- 10 4. In a type-writer, the combination of an automatic step-by-step carriage-feed or letter-spacing mechanism and an automatic line-spacing mechanism with a spring-barrel actuated by a rack-bar mounted upon the carriage for storing power during the letter-spacing operation, a sliding bar for shifting

the rack-bar in and out of engagement with the letter-spacing mechanism, a fixed stop in the path of the sliding bar for actuating the latter to disengage the rack-bar, a lever operated by the line-spacing mechanism for actuating the sliding bar to engage the rack-bar, and a spring for holding the sliding bar in either of its shifted positions, substantially as described.

In testimony whereof I have signed my name to this specification in the presence of two subscribing witnesses.

JAS. F. McLAUGHLIN.
